UNITED STATES PATENT OFFICE.

HERMAN C. FISCHER, OF CLEVELAND, OHIO.

DESIGN FOR A CASTER-PLATFORM.

SPECIFICATION forming part of Design No. 33,467, dated October 30, 1900.

Application filed September 28, 1900. Serial No. 31,451. Term of patent 7 years.

To all whom it may concern:

Be it known that I, HERMAN C. FISCHER, a citizen of the United States, residing at Cleveland, in the county of Cuyahoga and State of Ohio, have invented and produced a new and original Design for a Caster-Platform, of which the following is a specification, reference being had to the accompanying drawings, forming a part thereof.

- 10 Figure I is a top plan of a platform, showing my new design. Fig. II is a side elevation of the same. Fig. III is a section on any one of dotted lines III, Fig. I, looking in the direction of the arrow.
- 15 The design comprises a saucer-shaped body portion *a*. Three arms *b*, *b*, and *b* are formed upon the upper end of the saucer-shaped body portion at equal intervals around the body portion. Each arm *b* is arranged radially to
- 20 and projects laterally of and outwardly from the body portion. Upon the upper side of each arm, centrally between the side edges of the arm, is formed a rib *c*, that is arranged longitudinally of the arm. Each arm *b* at
- 25 its outer end is enlarged to form a lug *e*, depending from the arm and terminating at its lower end in a circular cap *f*, that extends in under the arm and beyond the outer end of the arm. Each arm *b* is gradually reduced
- 30 in width toward its outer end to such an ex-

tent that the cap *f* at the outer end of the arm projects laterally beyond each side of the arm, as shown at *f'* in Fig. I. Consequently the caps *f* are not only visible in top plan beyond the outer ends of the arms, but are visible 35 also at opposite sides of the said arms. Within each cap is formed an annular recess or chamber *f*². (Shown in Fig. III.)

The essential and characteristic feature of my design includes the following: the saucer-shaped body portion having three arms *b*, *b*, and *b*, arranged equidistant apart around and projecting laterally and outwardly from the body portion, with the said arms gradually reduced in width toward their ends, and the 40 lugs formed upon the outer ends of the said arms and having at their lower ends the circular caps that extend not only beyond the outer ends of the arms, but beyond opposite sides of the said arms, as hereinbefore described.

What I claim is—

The design for a caster-platform, substantially as hereinbefore shown and described.

Signed by me at Cleveland, Ohio, this 20th 55 day of September, 1900.

HERMAN C. FISCHER.
